(57) **CLAIM**

The ornamental design for an exfoliating brush head, as shown and described.

DESCRIPTION

FIG. 1 is a perspective view of an exfoliating brush head in accordance with our new design, the brush head suitable for use with a personal care appliance;

FIG. 2 is a top view of the exfoliating brush head of FIG. 1; FIG. 3 is a front view of the exfoliating brush head of FIG. 1; FIG. 4 is a rear view of the exfoliating brush head of FIG. 1; FIG. 5 is a left side view of the exfoliating brush head of FIG. 1; and, FIG. 6 is a right side view of the exfoliating brush head of FIG. 1.

The broken lines immediately adjacent the shaded areas represent the bounds of the claimed design while all other broken lines are directed to environment and are for illustrative purposes only; the broken lines form no part of the claimed design.

1 Claim, 4 Drawing Sheets
